UNITED STATES PATENT OFFICE.

CHARLES DE QUILLEFELDT, OF NEW YORK, N. Y.

SIPHON-BOTTLE.

SPECIFICATION forming part of Letters Patent No. 361,400, dated April 19, 1887.

Application filed May 6, 1886. Serial No. 201,366. (No model.)

To all whom it may concern:

Be it known that I, CHARLES DE QUILLEFELDT, a citizen of the United States, and a resident of New York, in the county and State of 5 New York, have invented a new and useful Improvement in Siphon-Bottles, of which the following is a specification.

The invention relates to the top or valve mechanism of so-called "siphon-bottles," or 10 such as are used for carbonated mineral waters, in which the pressure of the carbonic-acid gas with which the beverage is charged is the means by which the liquid is expelled through the spout when the valve is opened.

15 The invention comprises improvements in the following respects: the construction and combination of parts, whereby, when the valve is open, direct communication is formed with the spout without an intermediate vertical 20 channel, while at the same time the packing around the valve-stem is pressed tightly around the same, so as to cause no leakage through the bore in which the valve-stem fits and without pinching the packing between the said valve- 25 stem and bore, and when the valve is normally closed the lever rests against a positive stop at the upper end of its stroke, so as not to lessen the throw on the depression or downward stroke needed to sufficiently open the valve; also, the 30 construction whereby the valve-lever is kept steady, instead of playing loosely, as heretofore, thereby making it more agreeable to operate and facilitating its depression in such a manner as to effect a gradual opening of the 35 valve and prevent sudden spurts of the liquid; also, the construction whereby the packing in the valve-rod tube tightens its grip around the valve-stem in proportion as the vertical pressure increases.

40 The improvement will be hereinafter fully described, and specifically pointed out in the claims, reference being had to the accompanying drawings, in which—

Figure 1 represents a vertical section of the 45 top and upper part of the glass of a siphon-bottle constructed according to my present improvement. Figs. 2 and 3 are detail sections of two modifications of the valve-stem packing.

50 A is the bottle, and B the ordinary glass tube reaching down nearly to the bottom of

the bottle, and through which the liquid is pressed up to the spout by the pressure of the gas within the bottle. The pipe B is provided at its upper end with the usual flanged top or 55 fitting, b, of soft metal, the upper end of which fits in a corresponding recess in the lower end of the top piece, C, which latter is united to the bottle by being threaded and screwed down upon the threaded ring a, made of two semi- 60 circular pieces which embrace the bottle-neck and are retained by the shoulder on the bottle-head, as usual. A packing-ring, b', makes a tight joint between the top piece, C, the flanged piece b, and the upper end of the bot- 65 tle simultaneously.

In line with the glass tube B the lower end surface of the top piece, C, is provided with a preferably spherical cavity, c, and in the side of the said cavity is formed the inner end opening, n, of the spout c'.

D is the tube in which the valve rod or spindle E is arranged, as usual. The bottom of the said tube D is concave at d, where it forms a seat for the packing of the valve-stem e, 75 which works in a bore through the bottom of the tube from the center of the cavity d to the center of the cavity c.

F is the valve, which is an elastic ball, preferably of rubber, held to the valve-stem e by 80 simply being sprung over its lower end, which latter is headed in the manner of an ordinary screw, and has a threaded shank working in a correspondingly threaded central socket in the spindle E, by which the distance from the 85 operating-lever and the valve may be accurately adjusted. The spindle E is made of soft metal, and has at its upper end, beneath its top flange, a transverse slot, d'.

I is the valve-lever, the inner part of which 90 is of hard metal, to which the outer part or thumb-piece, made of soft metal, is united in the casting. The inner end of the lever I is notched upon its upper surface, or formed in the shape of a hook, i', which enters a correspondingly-made little socket in the side of the tube D, and engages with the said notch a hard-metal pin, d², which is secured by being cast in place, so that neither pin nor socket will show from the outside of the casting. The 95 portion i of the lever I, by which it engages the spindle E, is of the same height as the slot 100

in which it fits, and its opposite upper and lower surfaces are curved to a radius of half the height of the slot, so that when the lever is depressed to move the spindle downward 5 and open the valve F the said portion *i* will always move evenly and without play in the slot *d*.

H is the valve-stem packing. This is made of a rubber tube, as shown in Fig. 2, or preferably of a hollow sphere, with diametrically-opposite perforations to receive the valve stem, as in Fig. 3. Upon the upper end surface of the said packing is placed a metallic washer, *g*, fitted to move up and down slightly in the bore 15 of the tube D. When the spherical packing is used, the contact-surfaces may be flat both above and below the valve; but when the packing is made in the tube shape, like that shown in Fig. 2, the lower surface of the washer *g* should be concave, so that in either case when the washer *g* is depressed against the packing H by the force of the ordinary spiral spring, *G*, which surrounds the spindle, the packing will assume the shape shown in Fig. 1, pressing, both at its upper and its lower end, tightly around the valve-stem *e*, the tightening increasing with the increase of the pressure upon the spring, as when depressing the lever I to open the valve for drawing liquid from the bottle.

30 The upper end of the spiral spring *G* (which heretofore always was arranged to bear against the under side of the end flange of the spindle, as shown in United States Patent No. 182,612, and consequently closed the valve independently of the greater or less steadiness of the lever) bears, as shown in Fig. 1, upon the under side of the lever at diametrically-opposite sides of the spindle. Consequently, the pressure of the spring *G* serves three purposes—40 namely, to tighten the valve F against its seat directly upon the spout-opening *n*, to depress the washer *g*, and thereby tighten the packing H around the valve-stem *e*, and to force the lever I upward as far as it can go and retain it there steadily in position and without play.

45 In putting the parts together, the lever I is inserted through a side slot, *s*, in the tube D, then through the slot *d* in the spindle E, and, while compressing the spring *G* sufficiently, the hooked end *i* is inserted in the little side socket underneath the fulcrum-pin *d*, which latter it immediately engages by the upward pressure of the spring.

To prevent the lever I from being easily 55 disengaged during an unnecessarily deep depression, it is provided at *i* with a small upward projection, for which room may be made by making a notch or indentation in the edge of the end flange of the spindle, and which 60 projection serves as a stop against the inner surface of the tube D, adjoining the upper end of the slot *s*. The said stop *i* prevents the lever from being pulled out without a special manipulation for the purpose. The upper end 65 of the tube D is covered by a cap, *d*, as shown in Fig. 1.

In siphon-bottles as heretofore constructed

the outlet or the channel to the spout was the same as the opening through which the valve-stem works, the spout-opening adjoining the 70 said channel a distance above the valve. Above the said spout-opening the spindle was surrounded with three flat washers, of metal, leather, and rubber, between which and the end flange of the spindle the spiral spring was 75 interposed, the valve-lever resting loosely upon the top of the spindle, being inserted through opposite slots in the valve-rod tube and pivoted by its perforated end to a cross-pin in one of the said slots. (See Patent No. 80 182,612, above cited.) The said construction induced a tendency to leakage through the valve-rod tube, and made no provision for keeping the lever steadily and firmly in contact with the spindle—defects which, by my 85 present invention, are overcome.

As samples of the state of the art previous to this application, in addition to the patent before mentioned, I refer to United States Patent No. 336,463; English Patents No. 2,049 90 of 1860 and No. 1,450 of 1882; also, French Patent No. 25,699 of 1860; and I do not claim anything shown in the said patents.

As shown and described in one of the above-mentioned patents, English Patent No. 2,049, 95 it is old in siphons to employ an elastic conical-shaped valve having a flat upper surface in connection with a correspondingly-shaped seat; but I have found by practical trial that such a valve is open to the following defects: 100 First, there is so much of the surface of the valve tightly wedged against the wall of the siphon and the valve-seat that it very soon sticks and wedges fast; second, when not wedged fast the continual friction to which it 105 is subject draws it out of shape, so that its lateral expansion is not sufficiently uniform to keep it tight; third, when made very short, as it must be in order to fit tight, the wedging prevents its upper flat surface from touching the flat valve-seat; fourth, under such conditions water will stay above the valve, 110 get foul, and mix with the beverage when the valve is opened.

By my invention, the walls of the valve and 115 valve-seat touching only one portion of the valve and being spherical like the surface of the valve, friction is reduced to a minimum, expansion is uniform, and close contact with the seat always insured.

I do not claim, broadly, a globular valve 120 resting in a semi-spherical seat—such as is shown in Patents Nos. 124,840 and 143,294. A loose globular valve free, when open, to play between two surfaces a distance apart is 125 impracticable for the present purpose, as it would close the inner glass tube, and thus prevent any liquid from entering the bottle when the siphon-bottle is inverted for filling. In order to work satisfactorily, it is necessary 130 that the valve-stem be tight-fitting in its bore, while the valve must be elastic, so as to adapt itself readily to the valve-seat opening. When the valve is elastic and globular and used in

combination with the tight-fitting valve-stem threaded into the spindle E, and surrounded by the automatically-adjustable packing H, tightening against the said valve-stem, and 5 with the spiral spring G and lever I, the pressure of the said spring (acting in connection with the elastic valve, capable of more yielding or compression than what is necessary to fit it tight against its seat) pushes the lever I 10 always up to its absolute stop in the slot s, so as to insure the same throw in depressing it to open the valve. If the valve were not elastic, the risk would be incurred that it would not be held tight by the spring unless the lever stop short of its stroke or before reaching the stop in the slot s, and consequently it would shorten the downward throw of the lever to that extent, and thus lessen the opening 15 between the valve and its seat.

20 In Patent No. 182,612, above mentioned, the non-elastic valve used is, to a certain degree, automatically adjustable by the valve-stem springing sidewise in the bore in which it is loosely fitted; but in that case the packing 25 around the spindle wears leaky, the hole in the washer surrounding the spindle wearing larger, and the siphon always leaks at the top when filling the bottle. My packing H in the present case automatically tightens around the 30 valve-stem and the latter slides tightly in its bore, so as not even to wear the packing by pinching it between the valve-stem and its bore, while the adjustment of the same in the spindle E forms a feature necessary, in combination with the elastic valve and packing, to regulate the distance between the valve-seat and the stop for the upper throw of the lever, to take advantage of the elasticity of the valve 35 for tightening the same without shortening the upstroke of the lever.

Having thus described my invention, what I claim as new, and desire to secure by Letters Patent, is—

1. In a siphon-bottle, the top C, provided 45 with the cavity c, having bore for the valve-stem, side opening leading to the spout, and circular valve-seat, in combination with the stem e, fitting tightly in the said bore and carrying an elastic valve fitting the said seat, the 50 self-adjusting packing H, surrounding the said stem e, the spindle E, spring G, and lever I, the said stem e being adjustable in the said spindle and the said spring acting to tighten the said packing around the stem and 55 to raise the said spindle and valve.

2. The combination of the valve-lever I, the slotted spindle E, the valve stem packing, and

the spiral spring G, the said spiral spring being interposed between the said packing and the said lever, so as to steady the latter by keeping it always pressed against the upper end of the slot in the said spindle while tightening the said packing, substantially as specified. 60

3. The combination of the valve-lever I, the slotted spindle E, the valve-stem packing, and 65 the spiral spring G, the said spiral spring being interposed between the said packing and the said lever, so as to steady the latter while tightening the said packing, and the said lever being provided with a circular portion, i, of 70 the same diameter as the height of the spindle-slot d', substantially as specified.

4. The combination of the valve-lever I, the slotted spindle E, the valve-stem packing, and 75 the spiral spring G, the said spiral spring being interposed between the said packing and the said lever, so as to steady the latter while tightening the said packing, the inner end of the said lever being provided with a hooked or notched portion, i, engaging the fulcrum-pin 80 d', and with a stop, i', acting against the inner surface of the tube D, to prevent disengagement of the lever, substantially as shown and described.

5. In a siphon-bottle, the combination of 85 the top piece, C, having concave bottom d in its tubular part D, and the valve-stem e, fitted in a hole through the said bottom, with a hollow elastic packing, H, and a rigid washer, g, surrounding the said valve-stem, and a spring, 90 G, acting upon the said washer for the purpose of compressing the said packing H endwise, to conform to the said bottom d and tighten with its upper and lower edges around the said valve-stem e, substantially as set forth. 95

6. In a siphon-bottle, the combination of the top piece, C, having bottom d in its tubular part D, and the valve-stem e, fitted in a hole through the said bottom, with a hollow globular perforated elastic packing, H, and a rigid 100 washer surrounding the said valve-stem, and a spring, G, acting upon the said washer, for the purpose of compressing the said packing H endwise, to conform to the said bottom d and tighten with its upper and lower edges around 105 the said valve-stem e, substantially as specified.

In testimony that I claim the foregoing as my invention I have signed my name, in presence of two witnesses, this 1st day of May, 1886.
